UNITED STATES PATENT OFFICE.

CHARLES W. MAYER, OF ROCHESTER, NEW YORK.

COATING-MACHINE.

1,283,851.

Specification of Letters Patent.

Patented Nov. 5, 1918.

Application filed March 31, 1913, Serial No. 757,833. Renewed March 27, 1918. Serial No. 225,110.

To all whom it may concern:

Be it known that I, CHARLES W. MAYER, a citizen of the United States, and resident of Rochester, county of Monroe, State of New York, have invented an Improvement in Coating-Machines, of which the following description, in connection with the accompanying drawings, is a specification, like characters on the drawings representing like 10 parts.

My present invention relates to coating machines and while having other and more general fields of usefulness is particularly designed and well adapted for the production of carbon paper, waxed paper and like carbonized, coated or impregnated paper or like fabric.

One of the prime objects of the invention is to provide a machine adapted to handle 20 paper rapidly and to coat the same evenly while keeping the paper smoothed out and free from wrinkles throughout, the method of handling being such that even very thin and delicate papers can be handled without 25 injury thereto, and the machine being adapted to apply coatings variable to a wide degree as to nature and thickness as required. A further object of the invention is to provide an improved mechanism for 30 smoothing or brushing out the paper preferably just before it is coated, so that when it is presented to the coating roll it is perfectly smooth and without creases or wrinkles. A further object is to provide 35 improved means for equalizing or spreading the coating, such means consisting in one preferred embodiment in a wire wound rod adapted to be rotated and vibrated as the paper passes thereover. A further object is 40 to provide an improved construction of dope pan and agitating devices therewithin adapted to keep the contents thoroughly mixed and agitated throughout the operation of the machine. A further object is to provide 45 an improved form of winding-on roll variable in size in a predetermined manner and adapted to serve for measuring purposes. A further object is to provide an improved mounting for the unwinding 50 roll. A still further object is to provide an improved combination of mechanism including a relatively large chilling or annealing roll around which the paper passes from the equalizing bar, affording a relatively extended surface contact for the requisite annealing or chilling action. The above and

other objects and features of the invention will be better understood from the following detailed description taken in connection with the accompanying drawings and will be 60 thereafter pointed out in the appended claims.

Referring to the drawings:

Figure 1 is a vertical lengthwise section through the machine;

Fig. 2 is a horizontal section showing the brushing out mechanism;

Fig. 3 is a front elevation thereof;

Fig. 4 is a plan view showing the main working parts;

Fig. 5 is a detail of a part of the dope pan and roll;

Fig. 6 is a transverse section through the equalizing bar and its support;

Fig. 7 is a central lengthwise section 75 through the winding-on drum;

Figs. 8 and 9 show in elevation and section, details of said drum;

Fig. 10 is a fragmentary detail of a modified form of dope pan;

Fig. 11 is a plan view of a portion of the dope pan showing a modified and in some respects preferred form of agitating device;

Fig. 12 is a sectional view showing the agitating member of the agitating device 85 of Fig. 11.

The paper is unwound from a roll *a* journaled at 1 on a carrier part 2 having roller rests 3 on the carrier base 4 which is adjustable on the frame 5 by a rack and pinion connection 6. The carrier part 2 is yieldingly drawn backward by a spring 7 secured to it and to an upright from the carrier part 4. From the roll *a* the paper passes over an ironing edge composed of a square 90 bar 9 detachably set in a seat at the top of a rigid support 10. The front of this support presents a smooth downwardly sloping face 11 over which the paper passes after bending at a sharp angle around the ironing edge 100 of bar 9. The bar 9 is removable and may be turned over to present each of its four edges successively for an ironing edge as required. Beneath the support 10 is a roll 12 arranged so that the paper as drawn down 105 from the ironing edge 9 is kept against the face 11 and this roll 12 is also arranged adjacent and just below the top of dope roll 13. As the paper passes down over the face 11 it is smoothed out preparatory to contacting to the dope roll, and for this purpose I provide brushes 14, 15 mounted on endless

belts. These belts are moved so that the respective brushes travel from near the center, in opposite directions toward the edges of the paper and for this purpose they are 5 mounted on rolls 16 on shafts 17, all these shafts being power driven, the outer ones from the inner ones by sprocket chains 18 and the inner ones by gearing 19, 20 from a shaft 21 which is in turn driven by a 10 sprocket chain 22 from main driving shaft 23. The brushes 14, 15 are guided and held in pressing engagement with the paper throughout their operative reaches by plates 24 over which the brush carrying belts designated 25 pass and the brushes together with 15 their supports are bodily adjustable toward and from the face 11 over which the paper passes by screw bolts 26 which engage the brush carrying frame 27 near each end there- 20 of and have swiveling engagement as at 28 with a relatively fixed frame or support portion 29 which rests on a cross seat on the main frame. The sprocket chain 18 may have suitable tensioning devices, shown as 25 rolls 30 adjustably mounted as seen at 31. The brushes 14, 15, constituting the lateral smoothing means present soft flexible surfaces for engaging the paper which yield easily in the direction of paper feed, as well 30 as in the direction of their own movement, so that the paper is brushed and smoothed out with a gentle though effective action. This flexible and pliable character of the smoothing element is of particular importance 35 in handling light and delicate papers, which it will be understood constitute a great part of the output in a machine of this character.

From the roll 12 the paper web passes 40 over the top of dope roll 13, being guided so as to press over some little area of the surface thereof and thence it is guided forward over an equalizing bar 32. It is to be understood that the dope roll 13 is power 45 driven by connections (not shown) so that its surface moves at a somewhat different rate from that of the advancing paper. To provide uncoated edges for the paper web, at option, I provide guard pieces 34 carried by 50 adjustably mounted arms 35 and covering the surface of the roll at its ends. The equalizing bar 32 is mounted in a seat provided therefor on a box support 36 shown as triangular and hollow to permit heating by 55 steam introduced therein. The equalizing bar 32 is formed as a circular rod having a close winding of wire thereon, which wire may be of different sizes as required for different thicknesses of coating. The bar 32 60 is rotated and at the same time given a vibratory endwise movement by the following devices. It has fixed thereto at its left end as seen in Fig. 4, a pulley 37 driven by a belt 38 from a pulley 39 on the dope roll 65 shaft which belt also drives a pulley 40 on

the shaft 41 of the front roll to be presently described. As the bar 32 is thus rotated it is also vibrated endwise by a rod 42 which has swivel connection 43 therewith, this rod having a roller 44 at its outer end which engages a cam face of a disk 45 fixed on the end of shaft 41, there being a spring 46 housed in the bar support for returning the bar and to keep it in contact with said cam face. The box support 36 for the bar 32 is supported at its ends on arms 47 pivotally mounted on the shaft 41 and adjustable by screw bolts 48 to move the equalizer bar up and down as required. After passing over the equalizer bar 32 the paper passes 70 down around a relatively large and hollow lower front roll 49 fixed on shaft 41 and thence up and backward over roll 50 which may be a second dope roll for coating the other side of the paper if required. 75 Thence the paper passes over a back tension roll 51 and a front tension roll 52, and guide rolls 53 to an adjustable winding-on roll 54 which is suitably driven with a light friction drive, just strong enough to wind 80 on the paper without injuring the same. 85

The dope pan 55 rests on a steam jacket base 56 and has in its bottom a foraminous plate 57 adapted to keep the pan contents agitated by a continuous vibration which is 90 imparted by an upright 58 carried by said plate engaging with a series of step cam shoulders on a disk 59 at the end of the dope roll, there being a spring 60 interposed to keep the upright 58 pressed against said 95 shoulders. These cam-shoulders shift said plate in one direction and whenever the upright 58 clears one of their high edges the spring 60 causes the plate to snap back or return rapidly in the other direction, jarring 100 it and vigorously agitating the dope, thus effectually preventing it from settling. The stirrer plate 57 may be of simple grate form as shown in Figs. 4 and 5 but I preferably make it of the special form shown in the 105 Figs. 11 and 12 wherein such a stirrer plate designated 57^a has a large number of spaced apart fins 57^b struck up therefrom to extend obliquely toward the end of the plate wherefrom it is actuated by the upright 58 and 110 spring 60. Thus as the plate moves back quickly after being released by the cam shoulders 59 under the influence of the spring 60 these oblique fins sticking up into the dope mass will lift the heavier and more 115 solid portions of the dope that tend to settle in the bottom of the pan, and mix the same thoroughly with the rest of the contents. The dope roll and the several guide rolls or drums are hollow and mounted on hollow 120 shafts so that they can be heated as required by the introduction of steam, or as is sometimes the case with the front roll 49, cooled by the introduction of a cooling agent. The 125 dope pan bottom may be provided with cor- 130

rugations 61 to strengthen the same and promote the circulation of heat.

The winding-on roll 54 is adjustable in size and for this purpose it is composed of 5 a series of bars 62 having beveled ends 63 engaged by expanding rings 64 which are moved in and out by nuts 65 engaged with threaded portions 66 on a rod 67 mounted within the hollow shaft 68 of the roll. The 10 ends of the winding-on drum are formed by disks 69 which engage against the ends of bars 62.

In certain operations where only one side 15 of the paper is to be coated instead of running from the front roll 49 up over the roll 50, the paper may pass directly from the front roll back to the tension roll 52 as indicated by the dot and dash line α in Fig. 1. The bar 9 which presents the ironing edge 20 to the paper is preferably adjustable in and out to a small extent on its seat, an adjusting device for this purpose being shown as a screw 79 which may be located centrally of the bar, thus permitting a small rocking self 25 adjustment of the bar on its seat to conform to the line of paper feed.

In use the unwinding roll α is set in proper position by means of the rack and pinion device 6 and the spring 7 acting on the auxiliary roller support 2 contributes to keep the paper web under even and uniform tension, permitting take up for unevenness in the unwinding roll as when it is more or less irregular in shape instead of truly cylindrical 35 and concentric with its axis, as is often the case. The described mechanism is adapted to iron and smooth out and completely eliminate wrinkles and creases as the web passes over the ironing edge 9 which removes all 40 longitudinal wrinkles. The web as it passes down the smooth face 11 is acted on by the brushes 14, which completely eradicate all lateral wrinkles or unevenness so that as the paper passes thence over the coating roll it 45 is effectively smoothed out and stretched ready to receive an even uniform coating from the dope roll. The guard plates 34 are optionally employed and may be of different widths as required for leaving uncoated margins 50 of the desired extent or these guards may be removed if no uncoated margin is desired. The guards may be adjusted laterally to various positions at the ends of the coating roll or intermediate thereof, so that 55 if desired the web may be coated in stripes with blank or uncoated spaces between them and along the margins of the web. This lateral adjustment is permitted because there are no parts immediately above the coating roll 60 which interfere with the guards. This adjustment can be effected while the machine is in motion to make it possible to conform to various widths of stripes or selvage edges of the paper. The dope is kept constantly 65 agitated and in a condition of uniform consistency by the constantly reciprocating agitator plate in the bottom of the dope pan, the fins 57^b when this form is used not only agitating the pan contents but also by reason of their oblique direction constantly throwing up the more solid portions of the dope which tend to set in the bottom. It will be understood that the spring plate scrapers 77 when these are used may be adjusted so as to press on the dope roll to the required extent 75 for moving just the right amount of dope so that the paper may be carbonized, waxed or otherwise coated as lightly as desired. The compression roll 78, is a material feature especially for use with the scraper elements 77 in coating lightly carbonized paper, insuring as it does that the paper will remove practically all of the adhering dope on the roll and also insuring the more even application of the dope. I consider the special 80 construction and operation of the wire wound equalizer 32 to be a very valuable and important feature of the invention, the wire on this rod being selected as to size with reference to the work which the rod is to 85 perform, i. e., being wound with relatively coarse wire for heavy coatings and with fine wire for lighter coatings. The constant turning of this rod by the belt 38 as described prevents accumulating of lint or other foreign matter at the line of contact and this feature is also very valuable as presenting 90 constantly changing contacting portions insuring longevity of service and even wear on the rod. The swivel device 43 permits the 100 jiggling device consisting of roller 44 and cam face 45 to operate for the required purpose of producing a wavy or zig-zag line in the coating without in any wise disturbing the rotation of the rod. The rod is also kept 105 evenly and effectively heated by reason of its special mounting support at the top of the hollow steam heated box 36, the triangular form of this box combining rigidity as a support with a form permitting the widest 110 adjustment without interfering with the travel of the paper. It is to be noted that the front roll 49 is of relatively large size where- 115 by it presents a comparatively large and extended area of contact to the paper for annealing or chilling the same as required according to the kind of paper being produced, this being a point of considerable importance in producing waxed or carbonized paper where only a minute superficial coating is 120 desired. The special arrangement of the tension rolls 51 and 52 which may be cooled by the passage therethrough of cooling fluid is such that not only is an adequate grip upon the paper secured for drawing the same 125 through the machines but the paper first passing adjacent to and over the roll 52 on its way to the roll 51 is cooled by the presence of the roll 52 but it contacts with the roll 51. The adjustability of the take-on 130

roll 54 is also a valuable feature of the invention since it permits the size of this roll to be gaged in accordance with predetermined data so that with a definite number 5 of turns of this roll or drum the user can know just how much paper has been wound thereon. I am aware that the invention can be embodied as to most of its features in other specific forms than those shown and I 10 therefore desire the present embodiment to be considered as illustrative and not restrictive and refer to the appended claims rather than to the foregoing description to indicate the scope of the invention.

15 Having described my invention what I claim as new and desire to secure by Letters Patent is:

1. An apparatus of the kind described, comprising means for feeding a web of paper, means for coating the same, and smoothing means arranged to engage the web adjacent to and in advance of the receiving side of said coating means and laterally movable in opposite directions 25 from the central portion of the web toward its edges.

2. Apparatus of the kind described, comprising mechanism for feeding a web of paper under tension and for coating the same, there being a smooth plane face over 30 which the paper passes prior to its coating, and smoothing means moving laterally over the paper and pressing it against said face to smooth the paper, said smoothing means presenting soft, yielding and flexible paper 35 engaging portions.

3. Apparatus of the kind described, comprising means for feeding a web of paper under tension, a coating roll in position for 40 coating the paper as it is fed, and means for smoothing the paper laterally, consisting in oppositely moving brushes adapted to engage the paper prior to the coating thereof, there being a smooth plane backing face 45 against which the paper is pressed as the brushes act thereon.

4. Apparatus of the kind described, comprising means for feeding a web of paper under tension, means for applying dope 50 thereto, and means for smoothing and ironing the paper consisting in a smooth face plate over which the paper is drawn while held against such face, a bar equipped with an ironing edge fitted to a side of said plate 55 and a laterally moving member acting against such plate to smooth and stretch the paper laterally.

5. Apparatus of the kind described, comprising mechanism for feeding paper and 60 treating the same with coating material, and means for equalizing the dope coating consisting in a relatively small rotary rod and means for turning the same in the operation of the machine, said rod being arranged in

position for the coated paper to be flexed 65 thereover at a substantial angle.

6. Apparatus of the kind described, comprising mechanism for feeding and coating paper, and an equalizer in position to engage the paper after the coating thereof, consisting in a relatively small circular rod having provision to receive rotary and endwise movement in the operation of the machine for the purposes stated, said rod being arranged in position for the coated paper to 75 be flexed thereover at a substantial angle.

7. Apparatus of the kind described, comprising mechanism for feeding and coating paper, and means for equalizing the coating consisting in a relatively small circular rod 80 presenting a scalloped contour, and means for continuously rotating said rod in the operation of the machine, said rod being arranged in position for the coated paper to be flexed thereover at a substantial angle. 85

8. Apparatus of the kind described, comprising mechanism for feeding and coating paper and means for equalizing the coating consisting in a rod of scalloped contour, a support for said rod throughout the length 90 thereof adapted to be heated and means for continuously rotating said rod in the operation of the machine, said rod being arranged in position for the coated paper to be flexed thereover at a substantial angle. 95

9. Apparatus of the kind described, comprising mechanism for feeding and coating paper, and an equalizer rod in position to engage the paper after the coating thereof, said rod presenting a scalloped contour and 100 having provision to receive combined rotary movement and endwise vibrations continuously in the operation of the machine, said rod being arranged in position for the coated paper to be flexed thereover at a substantial angle. 105

10. Apparatus of the kind described, comprising mechanism for feeding and coating paper, and means for equalizing the coating thereof consisting in a wire wound equalizer 110 rod equipped with mechanism for rotating the same and vibrating it endwise continuously in the operation of the machine, said rod being arranged in position for the coated paper to be flexed thereover at a substantial angle. 115

11. Apparatus of the kind described, comprising mechanism for feeding paper under tension and for coating the same, and means for equalizing the coating consisting in an 120 equalizer device having provision to present constantly changing paper engaging portions, said equalizer device being mounted in position to substantially change the direction of the paper web as it passes thereover. 125

12. Apparatus of the kind described, comprising mechanism for feeding paper under tension and for coating the same, and means

for equalizing the coating consisting in a circular rod having provision to receive rotation, the mounting of said rod being adjustable to cause it to deflect the path of the paper to a greater or less extent, and being such as to produce a substantial flexing of the paper in all positions of adjustment.

13. An apparatus of the kind described, comprising mechanism for feeding a paper-
10 web, a coating roll arranged to engage the web and provided at one end with an annular row of cam-shoulders, a dope-pan for supplying said roll, an agitator in said pan movable lengthwise of said roll and provided with a member which engages said shoulders to shift the agitator in one direction, and a spring for holding said agitator-member against said shoulders to shift the agitator in the opposite direction.

14. Apparatus of the kind described, comprising mechanism for feeding paper under tension, a coating roll to engage the paper, a dope pan to supply said coating roll, and an agitator mounted in said dope pan consisting in a plate in the dope pan bottom having an intermittent positive actuator in one direction and a spring to move it in the opposite direction, said plate having obliquely extending fins struck up therefrom.

In testimony whereof I have signed my name to this specification in the presence of two subscribing witnesses.

CHARLES W. MAYER.
